UNITED STATES PATENT OFFICE

JOHN F. O'CONNOR, OF CHICAGO, ILLINOIS, ASSIGNOR TO W. H. MINER, INC., OF CHICAGO, ILLINOIS, A CORPORATION OF DELAWARE

RAILWAY DRAFT RIGGING

Application filed November 17, 1930. Serial No. 496,137.

This invention relates to improvements in railway draft riggings.

One object of the invention is to provide in a railway draft rigging including the usual yoke member, shock absorbing means enclosed thereby and a coupler operatively connected to the yoke and cooperating with the shock absorbing mechanism, means for supporting the yoke and maintaining the proper alignment of the parts of the draft rigging in all operative positions thereof and preventing drooping of the coupler head, wherein the supporting means has engagement with the outer end of the yoke and is movable with the same in both buff and draft, thereby reducing wear between these parts to a minimum and at all times properly supporting the yoke.

A further object of the invention is to provide a mechanism of the character indicated in the preceding paragraph, which is particularly adapted for railway draft riggings, wherein the shock absorbing mechanism is compressed to a greater extent in buff than in draft, in other words, wherein the coupler has longer travel in buff than in draft. A proper support for the coupler shank is provided in all positions thereof, the supporting means being in the form of a shelf at the outer end of the yoke disposed outwardly of the connection of the coupler shank with the yoke.

A more specific object of the invention is to provide a supporting means for the outer end of a yoke of a railway draft rigging, operatively connected to the yoke for movement therewith, wherein the supporting means comprises link elements swingingly suspended from the car underframe structure and pivotally secured to the yoke.

A still further object of the invention is to provide a swinging yoke support of the character specified in the preceding paragraph, whereby the yoke is guided for longitudinal movement in a true horizontal path.

Another object of the invention is to provide in a railway draft rigging, having longer travel in buff than in draft including a shock absorbing mechanism, a yoke co-operating with the shock absorbing mecha-

nism, and a coupler connected to the yoke by means of a key extending through the coupler shank and the yoke and working in slots provided in the draft sills, wherein the key has the ends thereof, which work in the draft sill slots, reduced in size to permit the additional travel in buff, and that portion of the key connecting the coupler shank and yoke is of full size to provide the necessary rugged connection therebetween.

A further object of the invention is to provide in a railway draft rigging having longer travel in buff than in draft a yoke member and rear stop means so designed as to permit travel of the yoke inwardly in buff to provide for longer travel than in draft, and wherein the main front follower is reduced in thickness to less than the standard follower, thereby permitting the use of a correspondingly shorter yoke, thereby reducing the amount of clearance necessary to allow the required inward movement of the yoke in buff.

Other objects of the invention will more clearly appear from the description and claims hereinafter following.

In the drawing, forming a part of this specification, Figure 1 is a vertical, longitudinal, sectional view through the underframe structure of a railway car illustrating my improvements in connection therewith. Figure 2 is a horizontal, longitudinal, sectional view, corresponding substantially to the line 2-2 of Figure 1. Figure 3 is a longitudinal, vertical, sectional view of the underframe structure at the end of a railway car, illustrating a different embodiment of the invention, the center sill structure being shown in elevation. Figure 4 is a vertical, sectional view corresponding substantially to the line 4-4 of Figure 3. And Figure 5 is a vertical, sectional view corresponding to the line 5-5 of Figure 4, also illustrating, in dotted lines, different positions of the parts.

Referring first to the embodiment of the invention illustrated in Figures 1 and 2, 10-10 designate the channel-shaped spaced draft sills of the car underframe structure, to the inner sides of which are secured the

usual front stop lugs 11—11. The stop lugs and the sills have alined coupler key guide slots 12—12. The underframe structure of the car is provided with the usual rear stop casting 13, which also forms a filler block 5 between the sills and has the upper part of the center bearing formed thereon. As shown in Figure 1, the casting 13 is provided with the usual center pin receiving opening. The stop casting 13 has spaced, 10 forwardly projecting arms 14—14 forming the rear stops proper of the railway draft rigging. The coupler of the car is indicated by 15 and is connected to the yoke of 15 the draft rigging, as hereinafter more fully pointed out. The striking casting of the draft rigging is indicated by 16 and is fixed to the draft sills and the other parts of the underframe structure of the car.

As illustrated in Figures 1 and 2, I provide broadly a yoke A; a shock absorbing mechanism B; a cooperating front follower C within the yoke; a coupler key D; and a pair of yoke supporting links E—E.

The yoke A, which encloses the shock absorbing mechanism B, has the usual top and bottom arms 17—17 connected at the rear end by a vertical section 18. At the forward end, the yoke is hooded, said hood portion being defined by spaced side walls 19—19, a top wall 20 and a bottom wall 21. The spaced side walls of the hood are provided with alined coupler key receiving slots 22—22. The top wall 20 of the hood, as shown in Figure 1, is shorter than the bottom wall 21 and converges outwardly toward said wall. The bottom wall has a raised, thickened portion 23 at the outer or forward end thereof, which forms a support for the 30 coupler shank closely adjacent the head of the coupler. As shown, the supporting shelf or member 23 of the yoke is disposed forwardly of the coupler key receiving openings 22—22 thereof and in the normal position of the parts, as illustrated in Figure 1, 40 extends outwardly beyond the plane of the striking surface of the casting 16. A saddle plate 24, secured to the bottom flanges of the draft sills in the usual manner, guides the inner end portion of the yoke. At the forward end, the yoke is supported by the links E—E. Each link E is pivotally connected 50 at the lower end to the yoke A by means of a pivot member 25 in the form of a pin extending through alined openings in the bottom ends of the links and openings provided in depending lugs 26—26 formed integral with the bottom wall 21 of the hood of the yoke and located adjacent the outer end of the same, as shown in Figure 1. The upper ends of the links E are swingingly suspended from the striking casting 16 by means of a pivot pin member 27 extending through openings in the upper ends of the links and lugs 28 formed integral with the striking

casting. As will be evident, the yoke A is thus supported for sliding movement lengthwise of the railway draft rigging on the saddle plate 24 and by the links E—E. The links E—E being pivotally connected to the yoke and suspended from the striking casting in such a manner as to swing lengthwise of the car, provide supporting means for the forward end of the yoke, which is movable therewith, thereby reducing the wear of the parts by eliminating relative sliding movement between the supporting means and the yoke.

The shock absorbing mechanism B, which is disposed within the yoke, is of well known 80 form, and as herein shown, is of the friction type including a friction shell 29, friction means in the form of shoes 30 cooperating therewith and a wedge block 31 having wedging engagement with the shoes. As will be understood, the inward movement of the friction means is resisted by the usual spring disposed within the shell 29. The shock absorbing mechanism B is so designed that the same is capable of greater compression in 90 buff than in draft, that is in draft it is not compressed to its full capacity. The main follower C is in the form of a rectangular plate interposed between the wedge block 31 of the shock absorbing mechanism B and the inner end of the shank of the coupler 15. The follower C is preferably of lesser thickness than the standard follower usually employed. At the inner end, the friction shell 29 of the shock absorbing mechanism is provided with the usual follower member 32 formed integral therewith and cooperating with the rear stops formed by the arms 14—14 of the casting 13. In long travel draft gears, the friction elements project so far from the end of the cylinder that there is a tendency for the same to tip out of line, thereby causing excessive wear on the bottom wall section of the mouth of the friction shell. In order to counteract this tendency, I provide a thimble 33 securely fastened to the follower C engaging within and closely fitting a bore provided in the wedge block 31, thereby insuring correct alinement.

The coupler 15 is connected to the yoke A by means of the key D, the key D having the main body portion thereof, which is indicated by 34, extending through an opening 35 in the coupler shank and the openings 22—22 in the side walls of the hood of the yoke. The opposite ends 36—36 of the key, which are reduced in width, as clearly shown in Figure 2, work in the slots 12—12 of the draft sills. The key D is so designed that the front edges of the reduced portions 36—36 are in transverse alinement with the front edge of the main body portion of the key, while the rear edges of said reduced sections are forwardly offset with respect to the rear edge of the main body portion of the same.

As shown, the key is retained in position by headed pins 37-37, which extend through the offset ends thereof and are retained by any well known means, such as cotters. As most clearly illustrated in Figure 2, the slots 5 22-22 in the hood of the yoke are of considerably shorter length than the guide slots for the key in the draft sills, and in a buffing or inward movement of the coupler the main body portion of the key engages the inner 10 ends of the slots of the yoke before the reduced end portions of the key engage the inner ends of the slots of the draft sills, whereby the yoke is moved inwardly to a limited extent during a buffing action. In order to 15 accommodate this movement, clearance is provided between the inner end of the yoke and the bottom wall of the striking casting 18, the latter being cut away, as shown at 38. The operation of my improved railway 20 draft rigging during a draft action is as follows: The coupler 15 is pulled outwardly, thereby pulling the yoke A therewith through the medium of the key D, the shock absorbing mechanism B being compressed against the front follower C by the forward movement of the yoke. The draft movement of the coupler will be limited by engagement of the key D with the front ends of the slots of 25 the draft sills. During a buffing action, upon inward movement of the coupler 15, the main follower C will be forced rearwardly directly by the coupler, thereby compressing the shock absorbing mechanism B between the follower and the rear stop means 30 formed by the arms 14 of the casting 13. After the clearance between the main body portion of the key D and the rear end walls of the slots 22 of the yoke is taken up, the 35 yoke will be forced rearwardly in unison with the coupler, this movement being accommodated by the clearance 38 at the inner end of the yoke between the same and the filler casting 13. During this movement of the 40 coupler shank and yoke in unison, the key D will continue to move rearwardly in the slots 12 of the draft sills until the front follower C engages the forward end of the shell 29, the slots 12 of the draft sills being of sufficient 45 length to accommodate the necessary movement of the coupler key D. The buffing movement thus provided is in excess of the draft movement, as will be clear, especially upon reference to Figure 2, wherein the normal position of the parts is shown and the reduced ends 36-36 of the key D are illustrated as spaced a greater distance from the rear walls of the slots 12 than from the 50 front walls thereof. During the buffing and draft movement of the mechanism, the horizontal alinement of the parts is at all times maintained by the supporting means at the 55 front end of the yoke and the swinging link suspension for the yoke at this point.

By providing the form of coupler key shown in Figures 1 and 2, having the outer ends thereof reduced and the main body portion of standard width, the connection between the yoke and the coupler is of adequate 70 strength, while at the same time the longer travel of the parts is permitted without unnecessarily elongating the slots in the draft sills.

Referring next to the embodiment of the 75 invention illustrated in Figures 3, 4 and 5, the draft sills which are indicated by 110 are provided with stop lugs similar to the stop lugs illustrated in Figures 1 and 2, and a combined rear stop and filler casting, similar 80 to the casting 13. The front stop lugs and the sills are provided with alined coupler key guide slots 112, which are identical with the slots 12 hereinbefore described. The coupler is indicated by 115 and is connected by a 85 key J in all respects similar to the key D, hereinbefore described, to a yoke F, which is similar to the yoke A. A shock absorbing mechanism G and a front main follower H, similar to the corresponding parts B and C 90 hereinbefore described, are disposed within the yoke and cooperate with the stops of the sills in the same manner. The inner end of the yoke F is also supported by a saddle plate, not shown, similar to the saddle plate 95 24 illustrated in Figure 1. At the forward end, the yoke F has the lower wall thereof upwardly offset, as indicated at 123, to provide a supporting shelf for the coupler shank adjacent the head of the same. The forward end of the yoke at the shelf portion 123 thereof is supported by a pair of links K-K, which are in turn supported by rockers M-M fulcrumed on bearing means provided on the underframe structure of the car. 100 As shown in Figure 4, a pair of bearing brackets or blocks 150-150 are employed, the same being fixed to the outer sides of the draft sills 110-110. As indicated in Figures 4 and 5, the bearing blocks 150 are disposed substantially in transverse alinement 105 with the striking casting S, which is fixed to the underframe structure of the car and forms a spacing member between the front end portions of the draft sills. Each block 150 is provided with a bearing seat 151 for the lower end of the corresponding rocker M. Each rocker M has a rounded lower end portion 152 cooperating with the corresponding bearing seat 151 and a forked upper end 153 110 providing a bearing seat for pivot means in the form of a trunnion 154 provided on the inner side of the corresponding link K between the top and bottom ends thereof. The links K are thus supported for swinging 115 movement on the rockers M-M. At the lower ends, the links are connected to the yoke F by means of a pivot pin 155 extending through a pair of depending lugs 156-156 formed integral with the bottom 120 125 130

wall of the hood of the yoke F and alined openings in the bottom ends of the links K. The upper ends of the links are guided for vertical movement, the striking casting S being provided with spaced upstanding lugs 160—160, having vertical guide slots 157—157 therein which accommodate a pin 158 for vertical movement, the pin having its opposite ends secured in alined openings provided at the upper ends of the links M—M.

10 The operation of my improved railway draft rigging as illustrated in Figures 3, 4 and 5, is substantially the same as that of the structure described in connection with Figures 1 and 2, with the exception that the link supporting means illustrated in Figures 3, 4 and 5 provides for true horizontal movement of the forward end of the yoke F. This horizontal movement is obtained through the 15 rocking fulcrum supporting means for the links K—K.

As will be evident, in both a buff and draft action, as the yoke is moved inwardly or outwardly with respect to the car proper, the 20 supporting links K—K will swing on the trunnion members 154—154 cooperating with the forked upper ends of the rockers M, while the rockers will swing forwardly and rearwardly about the fulcrum points at lower 25 ends thereof, thereby causing the trunnions 154—154 of the links to travel forwardly and rearwardly, as indicated by the dotted line circles 161—161 in Figure 5. Due to the 30 rocking movement of the members M and the positioning of the pivots, as indicated at 161—161, the lower ends of the links and the pivot pin 155 will travel in a horizontal path, assuming the full and dotted line positions indicated by 159 and 162 respectively. During 35 this swinging movement of the links, the upper ends of the same will be guided in a substantially vertical path by the guide slots 157 in the lugs 160 of the striking casting with which the pin 158 cooperates.

40 I have herein shown and described what I now consider the preferred manner of carrying out my invention, but the same is merely illustrative and I contemplate all changes and modifications that come within 45 the scope of the claims appended hereto.

I claim:

1. In a railway draft rigging, the combination with the underframe structure of the car; of a yoke member; shock absorbing 50 means within the yoke; a coupler; means connecting the shank of the coupler to said yoke; and means supporting and guiding the yoke lengthwise of the car, including link means pivotally connected to the yoke and swingingly supported on the underframe structure of the car to guide said pivotal connection in a true horizontal path.

2. In a railway draft rigging, the combination with the underframe structure of the car; of a yoke member; and means support-

ing and guiding the yoke for movement lengthwise of the car including links pivotally connected at their lower ends to said yoke, guide means for the upper ends of said links, and members swingingly supporting 70 said links between the ends thereof.

3. In a railway draft rigging, the combination with the underframe structure of the car; of a yoke member; and means supporting and guiding the yoke for movement 75 lengthwise of the car including a link member pivotally connected at its lower end to the yoke, a member having rocking movement on the underframe structure of the car, pivot means inwardly of the upper end of said link, 80 swingingly supported on said rocking member, and means guiding the upper end of said link for vertical movement.

4. In a railway draft rigging, the combination with the underframe structure of the car; of a yoke member; means supporting and guiding the yoke for movement lengthwise of the car, including a pair of links pivoted to the yoke at the lower ends thereof, 85 and rockers supporting said links on the underframe structure of the car, said rockers being pivotally connected to the links and said underframe respectively; and means guiding the upper ends of said links including trunnion means on said links and vertical guideways therefor on the underframe structure of the car.

5. In a railway draft rigging, the combination with draft sills; of a striking casting fixed to said sills, said striking casting having guide members thereon provided with transversely alined vertical guide slots; bearing members on the underframe structure of the car disposed beneath said guide members of the striking casting; a yoke; a pair of rockers engaging in the seats of the bearing members, each of said rockers having a bearing seat at the upper end thereof; a link swingingly supported by each rocker, said link having a pivot lug between the ends thereof engaging the seat of the corresponding rocker, each of said links being pivotally connected at its lower end to the forward end portion of said yoke; and pivot means at the upper end of each link guided in the corresponding guide slot of the striking casting.

In witness that I claim the foregoing I have hereunto subscribed my name this 13th day of November, 1930.

JOHN F. O'CONNOR.
